UNITED STATES PATENT OFFICE.

CLYDE E. LEPLEY, OF BAYONNE, NEW JERSEY.

PROCESS FOR THE DISTILLATION OF PETROLEUM.

1,261,410.

Specification of Letters Patent.

Patented Apr. 2, 1918.

Application filed July 5, 1916. Serial No. 107,492.

To all whom it may concern:

Be it known that I, CLYDE E. LEPLEY, of Bayonne, in the county of Hudson and State of New Jersey, have invented certain new and useful Improvements in Processes for the Distillation of Petroleum, whereof the following is a specification, reference being had to the accompanying drawing, which shows diagrammatically and without detail the general type of an apparatus adapted for carrying out my process.

In order to understand the exact nature of the invention it is proper to point out that when petroleum is distilled by ordinary processes, the first effect is to distil off the gasoline and other lighter products, such initial distillation commencing at moderate temperatures, depending upon the character of the oil, and being in some instances carried to as high a temperature as 350 degrees F. The cessation of this part of the process is usually determined practically by observation of the specific gravity of the distillates, and when the still-man finds that such gravity reaches a predetermined point, (say for instance, 45 degrees Baumé), he recognizes that the initial distillation is complete. The next step thereafter is ordinarily the distillation of that portion of the oil which is classified as kerosene, such process being conducted at a higher rate of temperature, say from 350 to 450 degrees F., and being continued until practically all the kerosene has been distilled over, leaving only the usual residuum.

Under these circumstances, it is found that notwithstanding the fact that the temperature of the initial process is carried to a relatively high point, a very substantial percentage of light products suitable to be employed for gasoline manufacture, remains associated with the kerosene and ultimately comes over therewith in the later distillation. The result is that the ordinary distillation process fails to recover, as gasoline or other light product, the full amount actually present in the initial material, and that such substances, notwithstanding their comparatively low boiling points, remain in the kerosene and thus are lost for commercial purposes, and possibly may be detrimental to the kerosene itself.

By the process about to be described, I find that I can extract practically all the gasoline, and other products having relatively low boiling points, from a given

charge of petroleum, so that when the later stage of the process is conducted for the recovery of the kerosene, as such, the distillate will be substantially free from the lighter products.

In practising my invention I prefer to employ an apparatus of the general character shown in the accompanying drawing, which is a view, partly in vertical section and partly in side elevation, of the main elements.

In said drawing, 1, represents an oil tank having an oil feed pipe 2, connected with the source of supply, and at its upper portion a pipe 3, for admitting air, or other fluid, under pressure.

From the bottom of the reservoir 1, a pipe 4, leads upward through a flue chamber 5, having a central vertical flue 6, located axially within the chamber and connected with the walls thereof at top and bottom, so as to afford a completely inclosed annular interspace around the flue. The upwardly prolonged portion 7, of the pipe 4, is disposed in a spiral coil within this annular interspace and leads thence, as indicated at 8, to a downwardly directed discharge nozzle 9, located within the tower 10, arranged above the main still 11, and constituting the outlet, or delivery region, thereof. The pipe 8, is provided with a valve 12, for controlling the flow therethrough. The still 11, may be of any ordinary kind, being in this instance represented as arranged above a furnace 12, and being also provided with an internal steam heating coil 13, as an adjunct toward distillation. The still 11, communicates with the tower 10, and from the upper extremity of the tower a pipe 15, leads to the condensing apparatus, not shown. A source of heat such as a burner 18, is arranged beneath the flue chamber 5, and supplied with gas through the pipe 19.

In conducting my process, the still 11, is charged with petroleum as in ordinary practice, and the distillation is conducted in the usual manner by means of heat applied from the furnace 12, or steam coil 13, until the tests indicate that the gasoline, and other products having relatively low boiling points, have been driven off to the extent to which this method of treatment is available.

Thereupon, I introduce into the tower 10, a downwardly directed stream of highly heated petroleum from the tank 1, such petroleum being preferably of the same gen-

eral character as the initial charge in the still itself. In order to produce this result, the petroleum in the tank 1, is forced through the pipe 4, and coil 7, by means of 5 air pressure admitted through the pipe 3, and, in its passage through the coil 7, is heated to a temperature preferably from 800 to 900 degrees F., the pressure being preferably about twenty pounds. The heat 10 of the still proper 11, is itself raised to a point preferably a little below that at which kerosene of the desired gravity for that particular product would go over freely, and, while thus heated, the stream of highly 15 heated petroleum from the flue chamber 7, is injected in the direction to meet any vapor arising from the material in the still proper.

Under these conditions I believe that the 20 following re-action occurs. The vapors arising from the materials in the still proper comprise particles of gasoline and other light products, intimately associated with particles of kerosene, and if the application 25 of heat were continued in the ordinary way, the composite particles would go over together, but by contact with the opposing stream of highly heated petroleum, injected under pressure, it appears that the more 30 highly volatile portions of said stream associate themselves with the more highly volatile portions which are coming off from the material in the still, dissociating the latter from their intimate commingling with the 35 kerosene or heavier constituents so that the lighter particles both from the still charge and the injected charge combine and pass off together through the vapor pipe 15, while the less volatile portions of the injected 40 stream associate themselves with the less volatile portions coming off from the material in the still proper and tend to drop back into the still, or be retained therein.

The process thus described is continued 45 until the character of the distillate indicates that materials having a higher boiling point than that desired for the lighter portion of the product are beginning to come over. Thereupon, the injection of the 50 stream of vaporized petroleum is discontinued and distillation is resumed in the still at a higher temperature with the effect of carrying over the kerosene or other heavier oils to the desired degree. When this has 55 been fully completed, the residuum is removed from the still and the process is repeated.

Having thus described my invention, I

desire to state that the temperatures employed will vary with different kinds of initial material, but I have found that with ordinary crude petroleum from the Caddo Fields, the initial distillation of the gasoline and light products can be properly effected at a temperature of 300 degrees F., 60 in the still, and that, without raising this temperature by means of the furnace or steam coil, the injection of the stream of vaporized petroleum at a temperature of from 800 to 900 degrees F., and under a 65 pressure of about twenty pounds will give 70 good results.

I am aware that it is not new to employ a heated gaseous medium in connection with the distillation of petroleum, and I do not 75 broadly claim the use of such a medium, since my invention consists in an organized method of treatment which involves the use of a particular medium at a particular stage of distillation, and for a definite purpose 80 related to the conditions existing at that stage.

I claim:

The hereinbefore described process of distilling petroleum, which consists in first subjecting the petroleum to ordinary distillation, at a temperature not substantially above that adapted to drive off the gasoline and lighter products of a predetermined character, and conducting said process until 90 the character of the distillate indicates that the said lighter products have substantially ceased to come over, as such; then continuing the direct application of heat to the still but at a temperature not substantially exceeding the boiling point of the kerosene of the charge, and injecting into the delivery region of the still a stream of highly heated vaporized petroleum under pressure; collecting the lighter products driven off by 100 said last mentioned step until the character of the distillate indicates that they have substantially ceased to come over as such; and then subjecting the contents of the still to a temperature appropriate for the distillation of kerosene or other heavier products from the particular petroleum employed and collecting the same, substantially as set forth.

In testimony whereof, I have hereunto 110 signed my name at Philadelphia, Pennsylvania, this thirtieth day of June 1916.

CLYDE E. LEPLEY.
